UNITED STATES PATENT OFFICE.

JOHN LINDALL, OF BOSTON, MASSACHUSETTS.

RAILWAY-CAR.

1,097,803.

Specification of Letters Patent. Patented May 26, 1914.

Application filed March 24, 1913. Serial No. 756,365.

To all whom it may concern:

Be it known that I, JOHN LINDALL, a citizen of the United States, residing in Boston, in the county of Suffolk and State of Massachusetts, have invented an Improvement in Railway-Cars, of which the following description, in connection with the accompanying drawings, is a specification, like letters on the drawings representing 10 like parts.

This invention relates to a railway car of that class in which a plurality of car body units are pivotally connected together to move laterally one with relation to the other, and has for its object to provide an inclosed passageway from one unit to the other, which will afford protection against the weather for the passengers and allow the units to move vertically and laterally 15 with relation to each other without decreasing the protection of the passengers from the weather while in said passageway.

The invention is especially adapted for use on multiple unit cars substantially such as shown and described in another application Serial Number 691,869 filed by me April 19, 1912, in which an intermediate car body unit is pivoted to main car body units to be supported thereby.

30 In accordance with this invention, a main car body unit is provided with a bonnet, which is hinged or pivoted at its rear end to enable its front or free end to rise and fall, and which latter end is extended over 35 and rests upon the top of the end wall of the intermediate unit. The bonnet has cooperating with it curtains, which form the side walls of the passageway between the units, and said curtains have one end wound 40 upon rollers, which are extended up into the bonnet and below the floor of the passageway, so that the curtain may make a substantially tight joint with the under surface of the bonnet and with the floor of the 45 passageway. Provision is also made for forming a weather tight joint between the rollers and the main unit, as will be described. These and other features of this 50 invention will be pointed out in the claims at the end of this specification.

Figure 1 is a side elevation and section of a sufficient portion of a multiple unit car embodying the invention to enable it to be understood. Fig. 2, an enlarged detail in section longitudinally of the car to be referred to. Fig. 3, an enlarged detail in sec-

tion taken on the line 3—3 Fig. 2. Fig. 4, a detail showing the curtain in plan. Fig. 5, a detail in plan of the platform of the intermediate unit. Fig. 6, an enlarged detail showing the lower part of the curtain, and Fig. 7, an enlarged detail in section and elevation of the upper part of the curtain and the bonnet of a main unit.

Referring to the drawings; *a, b* represent 65 the main car body units and *c* the intermediate car body unit, of a multiple unit railway car substantially such as shown and described in the application referred to.

The intermediate unit *c* has its floor frame 70 provided with substantially central projecting end portions 10, which extend under the car bodies of the main units and are pivoted thereto to be supported thereby, and said end portions form the floors of 75 passageways between the end walls 12 of the intermediate unit and the end walls 13 of the main units *a, b*, which end walls are provided with the usual doorways. The floors 10 of the passageways are located at 80 a lower level than the floors 14 of the main units, and the present invention has for its object to provide said passageways with side walls and a top wall, which render the passageways substantially weather proof and 85 yet provide for movement of the car body units with relation to one another in different directions.

Inasmuch as the side and top walls of the passageways are of like construction, a detailed description of one will suffice to enable the invention to be clearly understood.

Referring to Figs. 1 and 2, the end wall 13 of the main unit *a* has pivoted or hinged to it above the doorway 15 therein, a bonnet 95 which is provided with a bottom 16, a top 17 and interposed ribs 18 which have inclined rear edges 19. The bonnet is pivotally secured to the end walls 13 of the main unit *a* by hinges 20, whose pivots are horizontally arranged so that the bonnet may have its outer or free end moved vertically, which is permitted by the inclined rear end of the bonnet, which extends upwardly away from the end wall of the main unit, 100 so that the top of the bonnet is separated from the end wall of the main unit by a space 21 of sufficient width to allow for vertical movement of the car body units with relation to each other, when the car is 105 running on portions of the track at different levels, and yet enable the free or outer

end of the bonnet to rest upon the end wall 12 of the intermediate unit.

The roof of the intermediate unit is provided with an end portion 22, which extends downwardly from the end wall 12 and forms with the upwardly inclined center portion 23 of the roof, a gutter 24, which runs transversely of the intermediate unit and over which the free end of the bonnet projects to shed water into the gutter.

The space 21 between the rear end of the bonnet and the end wall of the main unit is closed by a strip 25 of canvas or other flexible material, which may form an extension of the covering 26 for the bonnet, and is left slack so as not to interfere with the vertical movement of the bonnet, and which forms a weather tight joint between the bonnet and the end wall *a* of the main unit.

The passageway between the end walls 13, 12 of the main and intermediate units is closed at its sides by curtains 30 of canvas or other suitable flexible material, which are wound upon rollers 31, each of which is journaled at its lower end below the upper surface of the floor 10 of the passageway, in a bracket 32, see Figs. 2 and 6, secured to the end wall 13 of the main unit and having its horizontal member extended into a curved slot 33 in the floor 10 of the passageway, and has its upper end extended through a hole 34 in the bottom 16 of the bonnet and journaled in a bracket 35 fixed to the end wall *a* of the main unit. It will be observed, that the roller 31 is extended above the bottom of the bonnet and below the upper surface of the floor 10 of the passageway, which enables the curtain to make contact with the under surface of the bonnet and with the upper surface of the floor 10, see Fig. 8, and thus make a weather proof joint at the top and bottom of the passageway. The front end or edge of the curtain is secured to the end wall 12 of the intermediate unit in any suitable manner, as for instance by a cleat 37 and screws 38, see Fig. 4, and as the intermediate unit rises and falls with relation to the main unit and vice versa, the top and bottom edges of the curtain remain in engagement with the bonnet and with the floor of the passageway.

The slots 33 in the floor 10 are made on curves with the pivot 39 for the intermediate unit as a center, so that the intermediate unit can move laterally with relation to the main unit, as when rounding a curve especially of short radius, and in this lateral movement, the curtain remains in contact with the bonnet and the floor of the passageway and makes a weather proof or tight joint therewith. In the lateral movement of the intermediate unit, the curtain

on one side is unwound from its roller, and the curtain on the other side is wound upon its roller, in a manner well understood, that is, after the manner of the ordinary window curtain.

The curtain may and preferably will be provided at its top and bottom edges with reinforcing or wearing strips 40, 41 of leather or other suitable material. A weather tight joint between the main unit 75 and the curtain roller is effected as herein-shown, by a strap 43 of rubber or other suitable material, which is fastened at one side to the main unit and has its other side bearing against the curtain on the roller as shown in Fig. 4. The floor 10 may be beveled or inclined at its outer sides or edges as at 45, see Fig. 6, to shed the water which runs down the curtain on the outside thereof.

From the above description, it will be seen that the passageway from one car body unit into another is closed substantially weather tight, and remains so in all movements of the car body units with relation to each other.

I have hereinshown the invention as embodied in a multiple unit car, but it is not desired to limit the invention to the particular construction of car hereinshown.

Claims.

1. In a railway car of the class described, in combination, main car body units, and an intermediate car body unit having its floor extended under the car bodies of the main units and pivoted thereto to move laterally therewith, said units having end walls separated from each other to form a passageway between the main units and the intermediate units, bonnets pivoted to the end walls of the main units to move vertically and having their free ends extended over and resting upon the end walls of the intermediate units, curtain rollers carried by the main units on opposite sides of said passageways and extended above the bottom of the said bonnets and below the upper surface of the floor of said passageways, curtains having one end wound upon said rollers and their other ends secured to the intermediate unit and having their upper and lower edges in close proximity to the bottom of the bonnet and to the floor of said passageway respectively, substantially as described.

2. In a railway car of the class described, in combination, main car body units, and an intermediate car body unit having its floor extended under the car bodies of the main units and pivoted thereto to move laterally therewith, said units having end walls separated from each other to form a passageway between the main units and the intermediate units, bonnets pivoted to the end walls of the main units to move vertically and having their free ends extended over and rest-

ing upon the end walls of the intermediate units, curtain rollers carried by the main units on opposite sides of said passageways and extended above the bottom of the said 5 bonnets and below the upper surface of the floor of said passageways, curtains having one end wound upon said rollers and their other ends secured to the intermediate unit and having their upper and lower edges 10 in close proximity to the bottom of the bonnet and to the floor of said passageway respectively, flexible means covering the space between the rear wall of the bonnet and the end wall of the main unit, substantially as 15 described.

3. In a railway car of the class described, in combination, main car body units, and an intermediate car body unit having its floor extended under the car bodies of the main 20 units and pivoted thereto to move laterally therewith, said units having end walls separated from each other to form a passageway between the main units and the intermediate units, bonnets pivoted to the end walls of 25 the main units to move vertically and having their free ends extended over and resting upon the end walls of the intermediate units, curtain rollers carried by the main units on opposite sides of said passageways 30 and extended above the bottom of the said bonnets and below the upper surface of the floor of said passageways, curtains having one end wound upon said rollers and their other ends secured to the intermediate unit 35 and having their upper and lower edges in close proximity to the bottom of the bonnet and to the floor of said passageway respectively, and means secured to the main unit and coöperating with the curtain roller to 40 form a substantially weather proof joint between the said roller and the end wall of the main unit.

4. In a railway car of the class described, in combination, car body units pivotally 45 connected and having end walls provided with doorways and separated from each other to form a passageway between them,

a bonnet pivoted at one end to one unit to move vertically and having its free end resting upon the other unit, flexible curtains forming side walls of said passageway and having their upper edges in close proximity to the under surface of said bonnet and their lower edges in close proximity to the upper surface of the floor of said passageway, 55 means for securing the said curtains to one of said units, and means carried by the other of said units upon which said curtains are wound and from which they are unwound, substantially as described. 60

5. In a railway car of the class described, in combination, car body units connected together to permit of vertical and lateral movements and having end walls provided with doorways and separated from each other to form a passageway between them, and a bonnet pivoted at one end to one unit to move vertically and having its free end extended over the other unit, substantially as described. 70

6. In combination, a railway car provided with a doorway in its end wall, and a bonnet pivoted to said end wall above said doorway and extended in the direction of the length of the car, and means for forming a substantially weatherproof covering for the joint between the rear end of the bonnet and the car body. 75

7. In a railway car of the class described, in combination, car body units connected together to permit of vertical and lateral movements and having end walls provided with doorways and separated from each other to form a passageway between them, and a bonnet to cover said passageway pivoted to one of said units to move vertically. 80

In testimony whereof, I have signed my name to this specification in the presence of two subscribing witnesses.
